ABSTRACT OF THE DISCLOSURE

A tilting file is provided in which a casing includes a framework on which is mounted a horizontal rod from which is suspended a cradle-type platform adapted for supporting a plurality of flat folders having at the upper corner extremities thereof hooks which are hooked over and therefore pivotally engaged with the horizontal rod. A catch is provided for retaining the platform within the casing, there being further provided a release or control by means of which the catch is rendered ineffective so that the platform under the influence of gravity will pivot outwardly from the casing so that the folders protrude angularly from the casing. A limit device is provided to limit the amount by which the files will protrude and a masking device is provided to conceal the bottom of the platform and to move yieldingly against the bottom of the platform as the platform moves into its protruding position.

DRAWING

FIG. 1 is a front perspective view of a file provided in accordance with a preferred embodiment of the invention;

FIG. 2 is an end perspective view of the apparatus of FIG. 1 illustrating the folders in protruding attitude;

FIG. 3 is a perspective view of an internal framework of the casing of the apparatus of FIGS. 1 and 2 illustrating the manner in which the folders are supported;

FIG. 4 is an end view of the apparatus illustrated in FIG. 3 with the folders in withdrawn attitude;

FIG. 5 is a view corresponding to FIG. 4 with the folders in protruding attitude;

FIG. 6 is a perspective view of the cradle-type platform on which the folders are supported;

FIG. 7 is a partially broken away view illustrating the catch mechanism employed in accordance with the invention and the operating system therefor; and

FIG. 8 illustrates the masking element employed in the apparatus of FIGS. 1-5.

DETAILED DESCRIPTION

This invention relates to files and more particularly to the type of file wherein a plurality of folders are arranged for selective removal.

It is an object of the invention to provide an improved file of the above-noted type which is readily operated to provide access to stored articles, such as correspondence and documents.

It is another object of the invention to provide an improved file construction which effects a major economy with respect to the utilization of space.

Yet another object of the invention is to provide a file which in operation will have a beautiful appearance and may be very well matched with various styles of office furniture to preserve the overall appearance of the office in which such file is installed.

To achieve the proper and other of the objects of the invention, there is proposed a casing within which is supported a framework on which is installed a horizontal rod from which are concomitantly suspended a cradle-

2

type platform and a plurality of folders, the folders being supported by hooks on the rod while, at the same time, resting at their bottoms on the cradle-type platform.

The platform is pivotable from a withdrawn position to a second position in which the folders protrude angularly from the casing, in which position the folders are readily engageable for removal from the casing, this being effected simply by removing the hooks from the aforesaid rod.

As will be seen, it suffices simply to press a button whereupon all of the filed folders turn through an angle of about 40 degrees, moving from a vertical stored attitude to a tilted position and automatically projecting from the file as a result of which the folders can be engaged and removed as aforesaid.

The angle of inspection which is thereby provided with respect to the files greatly facilitates locating the desired folder and after the folder is located, the removal of the folder from the file is an extremely simple matter as has been indicated above. At the same time, the replacing of the removed folder back into the file is a matter of extreme convenience as is afforded in accordance with the various features of the invention.

The cabinet of the apparatus of the invention may be made of wood or steel, or aluminum or the like and the internal mechanism is of an extremely simple design which may be made up, for example, of rectangular steel tubes, thereby effecting an extreme economy both with respect to labor and materials.

The above objects, features and advantages of the invention will become more apparent from the following detailed description of a preferred embodiment as is illustrated in the accompanying drawing.

In the drawing, the file F is seen to comprise a cabinet C supported on four legs L. The front legs may be provided with adjustable members A whereby the height of the assembly and the tilted attitude thereof can be compensated with respect to carpets, floor coverings and the like.

In the illustrated embodiment, there are provided two compartments or chambers K1 and K2 with respect to which there are further provided doors D having handles H by means of which the doors can be opened to expose the contents of the cabinet.

FIG. 1 illustrates one of the compartments K1 in closed condition with the doors concealing the opening of the compartment and therefore concealing and protecting the contents thereof. This figure also illustrates the doors of compartment K2 open, thereby exposing the folders in the compartment K2 as well as various other operating members which will be discussed hereinunder. It is to be noted that the doors D can be of the concealed type which are withdrawn into the cabinet upon being opened.

FIG. 2 illustrates the folders which have been brought from a vertical concealed attitude to an attitude in which they are exposed, by reason of angularly protruding from their respective compartments. The manner in which this is brought about will be next explained hereinafter.

Referring next to FIG. 3, it is seen that within the cabinet C is mounted a frame or framework 1 which is concealed within the cabinet and defines with the latter the chambers in which the folders are to be accommodated.

The framework 1 supports a horizontal rod 2 which may be fabricated of steel tubing, aluminum or the like. The frame 1 is provided with a plurality of legs 3 supporting the frame 1 within the cabinet. As an alternative these legs may protrude from the cabinet and constitute the legs of the complete file.

In order to provide for suspension of the folders, there are provided two depending arms 4 which are pivotally

engaged with the horizontal rod 2 which may be held in position in the frame 1 by the use of locking members or screws 5.

The depending arms 4 pivot as will be described in greater detail hereinafter, but are limited in forward movement due to the provision of cooperating limit members 6 and 6'. The member 6' may be a rubber block or the like fixed on the frame 1, whereas the limit member 6 on each arm 4 will be a flap which is integral or rigid with the associated arm.

The arms 4 are preferably of a metal, such as steel, and cooperate with a platform 7 to constitute a cradle-type platform on which rest the folders which are indicated generally at Y. The folders Y are flat book-type folders of generally rectangular configuration which not only rest on the platform 7, but are moreover supported in a second manner as will be indicated hereinafter.

In order to retain the platform 7 in withdrawn or retracted attitude, there is provided a catch system to be hereinafter described. This catch system is controlled by a control indicated generally at 8, including an exposed operating member 9 forming part of an operating system which will be hereinafter described.

It is to be noted that the platform 7 is normally urged to the forward or protruding attitude solely under the influence of gravitational forces acting to move the platform 7 pivotally about horizontal rod 2, since the platform 7 is pivotally supported at a corner thereof offset from the center of gravity of the platform as shown in FIGS. 4 and 5.

Also to be noted as a further feature of the invention is the masking element 11 which conceals the opening beneath the platform 7 and, as will be shown, rides yieldably against the bottom of the platform as the platform 7 moves into the protruding attitude as will also be seen hereinafter.

Referring also to FIG. 7 it will now be seen that the file of the invention incorporates a catch mechanism 12 provided with a latch stop 12'; there being also incorporated as part of an operating system, a latch release rod 14' which is urged away from the catch arrangement by means of a spring 13. The latch release rod 14' is connected to the operating member or button 9 by means of which the rod 14' is given an axial displacement against the catch mechanism 12.

The catch mechanism is yieldingly urged to a position of engagement with a rear cradle curb 15 installed at the back of the platform 7 and yieldably engages a notch 17 in the cradle curb 15 under the influence of spring 14 by means of which the platform 7 is held in retracted or withdrawn position in which the folders are retracted within the respective chambers.

Finally, each of the folders Y is provided at an upper corner extremity with a hook 16 fabricated of metal, plastic or the like, the hook detachably engaging in pivotal manner around the rod 2 whereby the folders Y can be displaced with the platform 7 and readily removed from the cabinet.

FIG. 8 illustrates that the springs 10 are engaged with the extremities of a bent rod forming part of the masking flap 10 whereby a yieldable tension is applied to said rod when the platform is moved into its retracted position, thereby drawing the flap 11 into the illustrated vertical attitude.

In operation, a plurality or multitude of folders Y are supported in book-like relationship on the platform 7, the platform 7 being in the retracted position illustrated, for example, in FIG. 1. By manual engagement of the operating member 9 supported in element 8, the rod 14' is given an axial displacement against spring 13 and disengages catch 12 from notch 17 thereby allowing the platform 7 to tilt to its forward position as shown in FIG. 5, due to the offset position of the center of gravity of platform 7 and the folders carried thereby with respect to a pivot axis passing through rod 2. The platform 7 tilts forward until limit element 6 engages limit element

6', the platform 7 then being in the position whereat the folders protrude angularly from the cabinet or casing as is illustrated, for example, in FIGS. 2 and 5.

At this time the angle through which the folders have moved is constituted, for example, by an angle lying within the range of 15-60°. Preferably, the angle through which the folders move is an angle of about 40°. The folders then protrude from the associated cabinet or casing by an amount which makes them readily accessible. At the same time, as a further feature of the invention, the folders have their exposed side edges at a position whereat these edges may be readily inspected to determine the information contained within the respective folders.

When a folder has been removed, such as by simply lifting the same from the platform 7 and disengaging the respective hook 16 from the rod 12, and the contents of the folder used, the respective folder may be readily returned to the position on the platform 7 by re-engaging its hook 16 with the rod 2. Thereafter the platform 7 may be returned to its withdrawn or retracted position by simply exerting a pushing force against the element 8. As previously explained, masking element 11 conceals the opening beneath platform 7, said element 11 undergoing pivotal movement as the platform tilts forwardly thereby stressing spring 10 to enable return of the masking element under the action of spring 10 when the platform is pushed back to its retracted position.

There will now be obvious to those skilled in the art many modifications and variations of the construction set forth above. These modifications and variations will not depart from the scope of the invention as defined by the following claims.

What is claimed is:

1. A storage device comprising a casing provided with at least one internal chamber which opens externally, support means to support an article to be stored selectively in a stored first position wherein the article is withdrawn into said chamber in a first attitude and an accessible second position wherein the article is moved from said first attitude and protrudes partially from said casing to be accessible, means pivotally supporting said support means from said casing such that said support means is urged by gravity to move from said first position to said second position, and control means to hold said support means in said first position and prevent movement of the support means from the first to the second position, said control means being releasable to free said support means and move said article from said first to said second position under the influence of gravity.

2. A device as claimed in claim 1 wherein said chamber opens horizontally and said support means includes a platform pivotally suspended in said casing for pivotal movement about a horizontal axis between said first and second positions.

3. A device as claimed in claim 2 wherein said support means includes a horizontal rod in said chamber from which said platform is suspended, comprising generally flat folders standing in vertical attitude on said platform and hooks on the upper extremities of said folders, said hooks being pivotally engaged on said rod.

4. A device as claimed in claim 3 comprising spring means in said casing and normally urging the platform toward the second position in which the folders protrude angularly from said chamber.

5. A device as claimed in claim 4 comprising catch means controllably retaining the platform in said first position subject to the operation of said control means.

6. A device as claimed in claim 5 comprising cooperating limit means on said casing and platform to limit the protrusion of the latter from said chamber.

7. A device as claimed in claim 6 wherein said control means includes an operating system mounted on said platform and engageable with said catch means to operate the latter, said system being exposed outside of said chamber for manual operation.

8. A device as claimed in claim 7 comprising doors on said casing to close off said chamber.

9. A device as claimed in claim 7 comprising a masking flap below said platform and means yieldably supporting said flap which is thereby adapted to slidably and yieldingly engage the bottom of said platform as the latter moves from one position to another.

10. A device as claimed in claim 7 wherein said folders are rectangular book-type folders.

11. A device as claimed in claim 7 comprising legs supporting said casing in elevated position.

12. A device as claimed in claim 9 wherein the means

yieldably supporting said flap includes a rod coupled to said spring means.
